UNITED STATES PATENT OFFICE

121,801

DESIGN FOR A DISPLAY RACK FOR DRESSES OR THE LIKE

Della Halbert Whitehead, Del Rio, Tex.

Application May 20, 1940, Serial No. 92,482

Term of patent 14 years

To all whom it may concern:

Be it known that I, Della Halbert Whitehead, a citizen of the United States, residing at Del Rio, in the county of Val Verde and State of Texas, have invented a new, original, and ornamental Design for a Display Rack for Dresses or the like, of which the following is a specification, reference being had to the accompanying drawing, forming part thereof.

In the drawing:

The figure is a perspective view of a display rack, for dresses or the like, showing my design.

The characterizing feature of the design resides in the display rack of the configuration shown having its end supporting and top cross bar elements simulating cattle branding elements, as shown.

I claim:

The ornamental design for a display rack, for dresses or the like, as shown and described.

DELLA HALBERT WHITEHEAD.
